(No Model.)

J. W. DUNHAM.

MACHINE FOR BEVELING CLOTH BOARDS.

No. 257,564.

Patented May 9, 1882.

UNITED STATES PATENT OFFICE

JOHN W. DUNHAM, OF ALBANY, NEW YORK.

MACHINE FOR BEVELING CLOTH-BOARDS.

SPECIFICATION forming part of Letters Patent No. 257,564, dated May 9, 1882.

Application filed August 8, 1881. (No model.)

To all whom it may concern:

Be it known that I, JOHN W. DUNHAM, a citizen of the United States, residing at Albany, in the county of Albany and State of New York, have invented certain new and useful Improvements in Machines for Beveling Cloth-Boards; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

My invention relates to scarfing or beveling the ends of cloth-boards; and it consists in the construction of the parts and their combinations, by which the machine is improved.

In the drawings, Figure 1 represents an up-right side view of the machine. Fig. 2 represents a front upright view. Fig. 3 represents a portion of Fig. 2, partly in section; and Fig. 4 represents a transverse sectional view on line *y y* of Fig. 2.

A represents the support of the machine.

B represents the crank-shaft, from which as it revolves motion is imparted to crank-wheel B'.

C is a pitman, attached at its lower end to crank-pin C' in wheel B', and at its upper end is connected to the reciprocating knife-stock by a noddle-pin, C''.

D is the head or knife stock, and is constructed so as to freely reciprocate perpendicularly between permanent guideways E E. The reciprocating stock D extends some distance below the knife, to have formed therein a perpendicular groove, *d*, and just below the knives a horizontal groove, *d'*, to receive sliding or adjustable gages F F.

ff are adjusting-screws to adjust the gages F to any desirable point with relation to the shearing-knives and the board to be operated upon, and work through flanges at the outer ends of the gages into the edge or side of the knife-stock.

f' f' are holding-screws which go through slots in the body of the gages, and thence into the knife-stock, to hold the gages firmly in place when adjusted.

G G are inclined flanges projecting forward from the upper part of the knife-stock, and are a part of or firmly affixed thereto with their plane faces toward each other, and each one has a bolt-slot, *g*, through it, by which means the knife is adjusted thereon by bolt *g'*.

H H are the slicing-knives, made fast to the flanges G, which cause them to be a trifle farther apart at their upper ends than at their cutting-edges, and as they project from the face of the knife-stock they flare or become farther separated from each other, so as to give the right bevel to the finished board X, as seen in Fig. 4. The outer and forward cutting-edges, *h*, of knives H, in their downward reciprocation, take hold of the wood on the side of board first, and as the knife advances downward continues to cut until the heel of the knife cuts the point of the board, thus producing a shear, and consequently a clean cut, even when the wood is cross-grained.

I I' are guide-rollers, between which the board X is fed truly into the machine while resting on any solid support; or I' may be only an upright board against which the cloth-board rests while being cut. The cloth-board being cut to the length required, the gages F F are adjusted to allow the thickness of the board to freely slide between them and centrally between the cut of the knives. When the gages are secured in that position, and the guide-rollers also adjusted, the board is forced between the rollers or roller and guide-board into groove *d*, the bottom of which is on the same plane as the heel-cut of the knives or the face of the knife-stock. When in the downward reciprocation of the knife-stock the gages first center the upper edge of the board with relation to the cut of the knives, and as the knives continue downward the board, whether warped, corrugated, or straight, is equally sheared on both sides, because the gages are close below the cut of the knives, and they guide the board its whole width centrally to the knives; and without these gages a bent or warped board could not be evenly cut or sheared on opposite sides. The groove *d*, being wider than the thickness of the board, allows a warped or bent board to be perfectly

and truly cut or sheared off on opposite sides,

as its lower edge can be at either side of the groove without detriment to the perfect slicing of the board.

Having thus described my invention, what

5 I claim is—

In a machine for scarfing or beveling cloth-boards, the combination of the reciprocating knife-stock D, having a perpendicular groove, d, horizontally-adjustable gages F, and the di-

verging and inclined knives H, as and for the 10 purposes described.

In testimony whereof I affix my signature in presence of two witnesses.

JOHN WARD DUNHAM.
